UNITED STATES PATENT OFFICE

98,690

DESIGN FOR A COMBINED SUPPORTING TRAY AND POWDER PAD DISPLAY

Samuel L. Pomerantz, New York, N. Y.

Application May 25, 1935, Serial No. 57,011

Term of patent 3½ years

To all whom it may concern:

Be it known that Samuel L. Pomerantz, a citizen of the United States and resident of New York, in the county of New York and State of New York, has invented a new, original, and ornamental Design for a Combined Supporting Tray and Powder Pad Display, of which the following is a specification, reference being had to the accompanying drawing, forming part thereof, and in which:

The single figure is a perspective view of the combined supporting tray and powder pad display, showing my new design.

The design consists of a tray provided with raised, ornamental ends and the tray contains

face powder pads, colored differently from the tray holding the pads, the entire article and contents being wrapped in a transparent covering.

The dominant feature of the design consists in the upwardly projecting end members of the tray, which are so shaped at their top portions as to merge or harmonize with the similarly-shaped upper edges of the powder pads which are held in display between said end members.

I claim:

The ornamental design for a combined supporting tray and powder pad display as shown and described.

SAMUEL L. POMERANTZ,
